BY

W. W. Williamson
ATTORNEY.

UNITED STATES PATENT OFFICE.

SAMUEL HEATH, OF ROXBOROUGH, PENNSYLVANIA.

REFLECTOR FOR GAS-FIXTURES.

1,317,494.

Specification of Letters Patent. Patented Sept. 30, 1919.

Application filed December 2, 1918. Serial No. 264,904.

To all whom it may concern:

Be it known that I, SAMUEL HEATH, a citizen of the United States, residing at Roxborough, in the county of Philadelphia, 5 and State of Pennsylvania, have invented new and useful Improvements in Reflectors for Gas-Fixtures, of which the following is a specification.

My invention relates to new and useful 10 improvements in reflectors for gas fixtures, and has for its object to provide a simply constructed device of this character which may be readily and quickly attached to a gas fixture and easily adjusted relative to the flame issuing from the gas burner, so 15 that the light may be reflected both horizontally and vertically downward.

A further object of the invention is to provide a frame for supporting two reflectors 20 upon a gas fixture, said frame being made of a number of parts capable of being adjusted relative to one another and including means for placing the parts when in position.

With these ends in view, this invention 25 consists in the details of construction and combination of elements hereinafter set forth and then specifically designated by the claims.

In order that those skilled in the art to 30 which this invention appertains may understand how to make and use the same, I will describe its construction in detail referring by numerals to the accompanying drawings forming a part of this specification, 35 in which:

Figure 1, is a side elevation of my improvement with parts shown in section and parts broken away to illustrate the construction, the same being shown upon a gas fixture.

Fig. 2, is a section at the line 2—2 of Fig. 1.

Fig. 3, is a perspective view of the L shaped bracket, and

Fig. 4, is a face view of the foot rest.

In carrying out my invention as here embodied, 2 represents an L shaped bracket consisting of a body 3 and a leg 4 at right angles thereto, the latter having a hole 5 adjacent its outer end for registration with the gas burner 6 of any suitable or approved construction which is mounted upon the ordinary gas fixture or bracket 7. The body 3 has an inturned flange 8 at each side thereof formed by bending the edges inward as will be readily understood and in the longi-

tudinal center of said body is formed a vertical or longitudinal slot 9.

Slidably mounted upon this L shaped bracket is a bowed upright 10 arcuate in cross section and provided throughout a portion of its length with extensions or straight flanges 11 adapted to slide in the inturned flanges 8 of the L shaped bracket. As will be seen from Fig. 2, this upright 10 bows outward and it is preferably constructed of resilient metal so that the straight flanges 11 will be forced into the inturned flanges 8 of the L shaped bracket thereby producing sufficient friction between the two parts to hold the upright in any adjusted position.

At its upper end this upright is provided with a projection 12 whereby a reflector 13 may be attached to the upright, said reflector being secured to the projection by some suitable means such as rivets 14. This reflector may be of any suitable shape or design best adapted for its use and the same may be imperforate or solid although I prefer to form a central opening 15 therein in order that the products of combustion from the flame of the gas burner may readily pass therethrough so that the reflector will not become darkened by dust.

Another reflector 16 is attached to the L shaped bracket by means of a screw or bolt 17 which passes through said reflector and registering with the slot 9, said screw or bolt having a nut 18 threaded thereon for holding the parts together in their adjusted positions and this nut normally is located within the bowed portion of the upright 10 so as not to interfere with the vertical adjustment of said upright. This reflector is preferably made of a solid piece of material except for the hole for the passage of the screw or bolt 17 although said reflector may also have an opening therein similar to the opening 15 in the reflector 13, but in the case of the reflector 16, a sheet of transparent material such as mica is disposed across said hole and in actual practice it has been found that said mica will reflect a certain amount of the light rays while permitting a certain amount to pass therethrough in order to light up the part of the room back of the reflector.

As the weight of the reflectors and other parts of the device is disposed at the unsupported end of the leg 4 of the L shaped bracket, I prefer to provide a suitable sup-

port therefor in the form of a foot rest 19 which is constructed from a relatively flat strip of material with a section at one end partly cut therefrom and bent up at right angles to produce an open end slot 20 for registration with the gas fixture 7 and form the lip or extension 21 which rests upon said gas fixture and in order that this foot rest may be attached to the L shaped bracket and 5 adjusted according to the fixture with which it is used, I form a vertical or longitudinal slot 22 therein which also registers with the screw or bolt 17 and this foot rest lies against the back or outer face of the body 10 portion of the L shaped bracket and is narrow enough to fit within the upright 10 so as not to interfere with the adjustment of the latter.

To further support the device in order 20 that it may be rigidly held upon the gas fixture, I provide a brace 23 formed from a strip of metal bent to form a split ring 24 for registration with the gas burner 6 which is then again bent to provide two 25 parallel strands 25 and 26 running from the burner to a point intermediate said burner and the body 3 at which point the strands are bent outward so as to gradually diverge toward the reflector at which point the ends 30 are bent inward so as to overlap and each of these overlapping ends has a hole therein which are adapted to align and through which passes the screw or bolt 27 the same also passing through the slots 9 and 22 with 35 a nut threaded thereon for holding the parts together or said screw might be mounted in a threaded hole in the body 3 below the slot 9.

In practice, the device may be readily applied to any ordinary gas fixture and the 40 parts adjusted so as to fit said fixture and give the best possible results. When in use, the rays of light issuing from the gas burner will be reflected downward by means of the 45 reflector 13 so that said rays of light will be concentrated upon one point and at the same time, the light will be reflected horizontally thereby greatly adding to the amount of light reaching a particular point of a room 50 which is quite essential when a person sitting in one part of the room desires to read and when said part of the room is some distance removed from the source of light.

Of course I do not wish to be limited to 55 the exact details of construction as herein shown, as these may be varied within the limits of the appended claims without departing from the spirit of my invention.

Having thus fully described my invention, 60 what I claim as new and patentable is:—

1. In a device of the character stated, an L shaped bracket comprising a body and leg located at right angles to each other, said

leg having a hole therethrough for registration with the burner of a gas fixture, a body 65 having a vertical longitudinal slot therein and provided with inturned flanges, an upright arcuate in cross section, straight flanges projecting therefrom and adapted to coact with the inturned flanges of the L shaped bracket whereby said upright may be slidably mounted thereon and frictionally held in any adjusted position, a lug or projection carried by the upper end of said upright, a reflector, means for securing said 70 reflector to said lug or projection, another reflector, and means passing through said last named reflector and registering with the slot in the body of the L shaped bracket for adjustably mounting said reflector on 75 said L shaped bracket.

2. In a device of the character stated, an L shaped bracket comprising a body and leg located at right angles to each other, said leg having a hole therethrough for registration with the burner of a gas fixture, a body 80 having a vertical longitudinal slot therein and provided with inturned flanges, an upright arcuate in cross section, straight flange projecting therefrom and adapted to coact with the inturned flanges of the L shaped bracket whereby said upright may be slidably mounted thereon and frictionally held in any adjusted position, a lug or projection carried by the upper end of said upright, a reflector, means for securing said reflector 85 to said lug or projection, another reflector, a foot rest comprising a flat strip of material having a section partially cut from one end thereof and bent upward at right angles to 90 produce an open end slot for registration with the gas fixture and form a lip to rest on said gas fixture, said foot rest also having a longitudinal slot therein, said foot rest adapted to contact with the outer face of the body of the L shaped bracket within the upright and having its slot in alignment with the slot in the body of the L shaped bracket, a reflector adapted to lie against the inner 95 face of the body of the L shaped bracket, a bolt passing through the reflector, the slot in the body of the L shaped bracket and the slot in the foot rest whereby the parts may be adjustably secured together, a nut on said bolt for drawing the parts together and holding them in their adjusted positions, a brace 100 having a circular or split ring portion for registration with the burner and further having parallel sections with diverging portions projecting therefrom, the ends of said 105 portions projecting inward and overlapping and means for attaching the overlapping ends of the L shaped bracket.

In testimony whereof, I have hereunto affixed my signature.

SAMUEL HEATH.
